UNITED STATES PATENT OFFICE.

WILLIAM E. SLOAN, OF CHICAGO, ILLINOIS.

CLOSET-SEAT.

1,337,730.

Specification of Letters Patent.

Patented Apr. 20, 1920.

Application filed March 17, 1913, Serial No. 754,721. Renewed September 4, 1919. Serial No. 321,658.

To all whom it may concern:

Be it known that I, WILLIAM E. SLOAN, a citizen of the United States, residing at Chicago, in the county of Cook and State 5 of Illinois, have invented a certain new and useful Improvement in Closet-Seats, of which the following is a specification.

This invention relates to closet seats and has for its object to provide a new and improved device of this description.

The invention is illustrated in the accompanying drawings wherein—

Figure 1 is a side elevation of the device embodying the invention;

Fig. 2 is a plan view of the device illustrated in Fig. 1;

Fig. 3 is a sectional view taken on line 3—3 of Fig. 1;

Fig. 4 is a sectional view taken on line 20 4—4 of Fig. 2;

Fig. 5 is a sectional view taken on line 5—5 of Fig. 2;

Fig. 6 is a perspective view of one of the parts of the hinge.

Like numerals refer to like parts throughout the several figures.

As illustrated in the drawing, I have shown a seat 1, connected by a suitable hinge to a bowl 2. The parts are arranged 30 so that the seat when released will automatically move upwardly so as to actuate the flush valve associated therewith. As shown in the drawings, the seat 1 is provided with a bracket 3 connected therewith, 35 said bracket having projecting parts 4 which engage a cross piece 5 mounted upon the seat post 6. Mounted upon this cross piece 5 is a sleeve 7 cut away at each end to form the shoulders 8. These shoulders are 40 engaged by the projecting parts 4 connected with the seat so that as the seat is moved, the sleeve 7 will also be rotated. Located between the projecting parts 4 is a spring inclosing part 9, the front end 10 of which extends around and engages the sleeve 7. The 45 sleeve 7 is provided with a friction piece 11 which engages the front portion 10 when the seat is lifted upwardly so as to cause frictional contact between the sleeve and said portion 10. Within the part 9 is a spring 12 which at one end engages a part 13 which in turn engages the sleeve 7. The spring at the other end engages the end piece 14 fixed to the part 9. The spring inclosing part 9 is 50 provided with shoulders 9^a and the projecting parts 4 are provided with opposed shoul- ders 4^a arranged to engage the shoulders 9^a so that when the seat is pushed down the engagement of said shoulders causes the spring engaging part 9 to be moved forward 60 so that the front end 10 thereof is moved out of contact with the friction piece 11 as shown in Fig. 5. An operating piece 15 is connected with the part 9 and has at the bottom a projecting part 16 which fits into a 65 slot 17 in a guiding piece 18 fastened to the seat post. The operating piece 15 is preferably split and is fastened to the part 9 by means of a set screw 19, and is arranged to make contact with a horizontally moving 70 part or push button 20, which operates a flush valve 21. This flush valve may be of any suitable construction, but I prefer to use the construction illustrated in my Patent No. 1,114,398, issued October 20th, 1914. 75 The operating part 15 is separate from said horizontally moving part or push button but is adapted to be brought into contact therewith when the seat is moved to the full line position shown in Fig. 1. 80

In the particular construction shown the flush valve is arranged so that it does not operate when the push button is released but does operate when the push button is pressed in, thus causing the bowl to be flushed, not 85 when the seat is pressed down but when it is released. When the seat is pressed down the shoulders 4^a engage the shoulders 9^a thereby moving the part 9 so that the operating part 15 moves away from the push 90 button. The spring 12 is now compressed and, since one end engages the part 13, which is prevented from moving by the sleeve 7 but which slides in the part 9, it will be seen that the part 9 is bodily moved 95 forward, thereby moving it out of contact with the friction piece 11. When the seat is released the spring 12 moves it back to the position shown in full lines in Fig. 1, at the same time moving the operating piece 15 100 toward the push button to actuate it, thereby permitting the valve to act to flush the bowl. At the same time, the part 9 moves bodily toward the sleeve 7 so that when the seat reaches its normal position as shown in 105 Fig. 1 the friction piece 11 will engage the front part 10. If now the seat is moved upwardly by hand it will be seen that the friction piece 11 moves along the surface of the part 10 and acts to resist movement and, 110 to hold the seat in any position, it may be moved to above the normal position. It will

further be seen that when the seat is pressed down against the bowl, the friction device is not operating and that the friction device remains out of operation while the seat 5 is being moved by the spring 12 back to its normal position shown in full lines in Fig. 1, but that the friction device becomes operative when any further movement is given 10 the seat so as to hold it in any desired position above the normal position.

I claim:

1. A closet seat device comprising a closet seat, a hinge therefor, a flush valve in proximity to said hinge, an actuating part for 15 said flush valve, a sliding part, an operating part connected therewith, adapted when moved in one direction to operate the actuating part of said flush valve, means connected with said hinge for sliding said sliding part in one direction when said seat is 20 moved, and a spring inclosed in said sliding part for sliding it in the opposite direction.

2. A closet seat device comprising a closet 25 seat, a hinge therefor, a flush valve in proximity to said hinge, an actuating part for said flush valve, and a connecting piece between said hinge and said actuating part but separate therefrom, for operating the 30 actuating part when the seat is moved to a predetermined position, said connecting piece having a horizontal movement, a connection between said connecting piece and said hinge, by means of which the connecting 35 piece is moved in one direction, and a spring inclosed in said connecting piece for moving it in the opposite direction.

3. A closet seat device comprising a seat, a bowl, a hinge for said closet seat, comprising separated projecting parts on the 40 seat, a cross piece with which they are connected, a flush valve in proximity to said seat, a push button device for actuating said flush valve, a sliding part connected with 45 said cross-piece and located between said separated projecting parts, means for sliding said part back and forth, an operating

piece connected with said sliding part and adapted to operate said push button to actuate said flush valve when the sliding 50 part is moved in one direction.

4. A closet seat device comprising a closet seat, a hinge therefor, a flush valve in proximity to said hinge, an actuating part for 55 said flush valve, a connecting piece between said hinge and said actuating part but separate therefrom for operating the actuating part, and a friction device associated with said hinge for holding the seat when moved to a predetermined position, and means for 60 bringing the friction device into action after the actuating part has moved to operate the flush valve.

5. A closet seat device comprising a closet seat, a hinge therefor, a spring connected 65 with said seat so as to move it away from the bowl a predetermined distance, a friction device associated with said hinge and means for rendering said friction device inoperative while the seat is being moved by 70 said spring.

6. A closet seat device comprising a closet seat, a projecting part connected therewith, a cross piece with which said projecting part is connected, a sleeve mounted on said cross 75 piece, a spring inclosing part associated with said hinge having a portion in proximity to said sleeve, a frictional connection between the sleeve and said portion, a connection between said spring inclosing part and the 80 projection on the seat so that when the seat is moved downwardly, the spring inclosing part is moved forwardly to compress the spring and render the friction connection inoperative, and a valve actuating piece connected with said spring inclosing part. 85

In testimony whereof I affix my signature in the presence of two witnesses this 14th day of March 1913.

WILLIAM E. SLOAN.
